US0D1103333S

(12) **United States Design Patent** (10) **Patent No.:** **US D1,103,333 S**
(45) **Date of Patent:** **** Nov. 25, 2025**

(54) **OIL FILTER**

(71) Applicant: **Briggs & Stratton, LLC**, Wauwatosa, WI (US)

(72) Inventors: **Adam J. Hellman**, Bayside, WI (US); **John Schneiker**, Muskego, WI (US)

(73) Assignee: **Briggs & Stratton, LLC**, Wauwatosa, WI (US)

(**) Term: **15 Years**

(21) Appl. No.: **29/796,711**

(22) Filed: **Jun. 25, 2021**

(57) **CLAIM**

The ornamental design for an oil filter as shown and described.

DESCRIPTION

FIG. 1 is a front perspective view from above of an oil filter, according to one embodiment;

FIG. 2 is a front perspective view from below of the claimed design of FIG. 1;

FIG. 3 is a front view of the claimed design of FIG. 1;

FIG. 4 is a rear view of the claimed design of FIG. 1;

FIG. 5 is a right side view of the claimed design of FIG. 1;

FIG. 6 is a left side view of the claimed design of FIG. 1;

FIG. 7 is a top view of the claimed design of FIG. 1; and,

FIG. 8 is a bottom view of the claimed design of FIG. 1.

Any portion of the article depicted in broken lines forms no part of the claimed design.

1 Claim, 7 Drawing Sheets
